WIRE LINE TESTER

Edgar W. Bagnell, Glendale, Calif., assignor, by mesne assignments, to Johnston Testers, Inc., Houston, Tex., a corporation of Texas

Application May 3, 1952, Serial No. 285,981

16 Claims. (Cl. 166—147)

This invention relates to oil well tools and particularly to a formation fluid testing tool. It is necessary in taking a sample of formation fluid with the usual tool to set packers, open and close several valves, and operate various other parts. Heretofore, these operations were performed by suspending the tool from a drill string and rotating and/or raising or lowering the drill string to cause corresponding rotary and linear movements of parts of the tool as well as imposing part of the weight of the drill string on other parts to set packers, etc. Use of a string of pipe is not only expensive but time consuming since the section must be assembled when running in a well and then disassembled when running out of the well.

It is a main object of the present invention to provide a formation fluid testing tool so constructed that it can be attached to the lower end of a wire line and be lowered in a well by means of the wire line, and then operated to take a sample of the formation fluid, thereby eliminating the expense and delay accompanying the use of a string of pipe. Another object of the present invention is to provide a formation testing tool as above described which utilizes the well fluid pressure to cause expansion of a pair of packers, and which packers can be collapsed by a pressure releasing arrangement actuated by an upward pull on the wire line.

Various other objects will be apparent from the following description taken in connection with the accompanying drawings wherein:

Figs. 1a, 1b and 1c illustrate successive sectional views of an oil well tool embodying the concepts of the present invention;

Figs. 2a, 2b and 2c are similar to views 1a, 1b and 1c, respectively, but show the parts in a subsequent stage of operation;

Fig. 3 is an enlarged fragmentary view more clearly showing the construction of the packers and the central packer head between said packers;

Fig. 4 is a still further enlarged view in section showing the internal construction of the central packer head;

Fig. 5 is a longitudinal sectional view of the valve locking arrangement with the parts disposed in running-in condition;

Fig. 6 is a view similar to Fig. 5 but with the parts disposed with the tool in packed condition;

Fig. 7 is a horizontal sectional view taken along line 7—7 of Fig. 6;

Fig. 8 is a view similar to Fig. 6 but showing a subsequent condition of the other parts, namely, when the device is in condition for running out of the well;

Fig. 9 is a view similar to Fig. 4 but showing the formation fluid valve in opened condition;

Fig. 10 is a view similar to Figs. 1a and 2a but showing the parts in condition for running out of the well.

Referring to the accompanying drawings, wherein similar reference characters designate similar parts throughout, the oil well tool disclosed includes a composite tool body, generally entitled 15, made up of various subs, cylinders,

2

housings, and the like, to be described hereinafter, and which is adapted to be suspended from the lower end of a wire line 17 by a connector generally entitled 19. Connector 19 includes a tool socket 20 receiving a wire line socket 21, which is secured to the lower end of wire line 17. A sub 22 connects tool socket 20 to a spring housing 23, which is urged toward the upper end of composite tool body 15 by a compression spring 25. Spring 25 surrounds an upwardly extending stem 27 on the upper end of body 15 and is contained between a nut 29 on the upper end of stem 27 and a flange 31 formed on the lower end of spring housing 23. Surrounding stem 27 is a stop sleeve 33 adapted to abut against nut 29 when the tool is suspended from wire line 17 because of the compression of spring 25 by the weight of the tool.

Included in composite tool body 15 is a valve sub 41 threadedly connected at its lower and upper ends to other housing parts to be described hereinafter. Valve sub 41 has formed therein well fluid inlet passages 43 adapted to communicate with a central passage 45 which in turn communicates with the upper end of a low pressure piston 47, the latter being slidably received within a low pressure cylinder 49 threadedly secured to lower end of valve sub 41. Passage of well fluid through passages 43 into central passage 45 is controlled by a packer setting slide valve 51, said valve being a part of a compound valve member generally entitled 53 to be described in detail hereinafter. As shown in Fig. 1b, slide valve 51 is disposed in a position to close ports 43 and prevent well fluid from being effective on lower pressure piston 47. Throughout the specification, the term "well fluid" will mean the fluid found in the well whether it be drilling fluid, water, or a combination of various fluids, whereas the term "formation fluid" or "connate fluid" will refer to the sample fluid which is to be taken.

Low pressure piston 47 is formed integrally with a high pressure piston 54, the latter fitting within a high pressure cylinder 55 secured to the lower end of the low pressure cylinder 49. Suitable O rings are provided on the exterior of low pressure piston 47 and on the interior of high pressure cylinder 55 to provide a sealing engagement between the cylinders and the pistons. When valve 51 is moved to its opened position, and well fluid becomes effective against low pressure piston 47, a body of hydraulic fluid, contained in tool body 15 and generally entitled 57, is forced downwardly through passages 59 formed in a top packer head 61 and into an upper tubular mandrel 63. Mounted on upper mandrel 63 is an upper expandable packer, generally entitled 65, adapted to be expanded by the hydraulic fluid into engagement with the walls of the well bore to form a seal therewith. Tubular mandrel 63 has suitable ports 67 for ingress and egress of hydraulic fluid therethrough to cause expansion and allow contraction of expandable packer 65.

Top packer head 61 is secured to the lower end of high pressure cylinder 55 (see Fig. 1b) and to the upper end of mandrel 63. The lower end of mandrel 63 is threadedly secured to a central packer head 69. There is provided a lower packer mandrel 71 secured at its upper end to central packer head 69 and at its lower end to a bottom packer head 73, said mandrel carrying therearound a lower expandable packer, generally entitled 75. Tubular mandrel 71 is also provided with lateral ports 77 for egress of hydraulic fluid outwardly to expand packer 75 and ingress of fluid to within tubular mandrel 71 to collapse expandable packer 75. The interiors of tubular mandrels 63 and 71 are communicated with one another by suitable passages formed in central packer head 69 and in the lower solid end of tubular mandrel 63, in a manner to be described hereinafter. At the present time it is sufficient to state that the interiors of the tubular mandrels are in communication with one

another so that when high pressure piston 54 is forced downwardly by the effects of well fluid pressure on low pressure piston 47, hydraulic fluid under a pressure greater than that of the well fluid (to a degree proportional to the ratio of the diameters of the pistons) will be forced through passages 59 in the top packer head 61 and pass through mandrel ports 67 and 77 and cause expansion of packers 65 and 75 so that the packers will form a seal with the walls of the well bore and, therefore, provide an annular formation fluid space around the exterior of central head 69 and between the packers.

Central packer head 69 has formation fluid passages 81 formed therein adapted to communicate with a formation fluid test tube 83 through a test valve to be described more in detail hereinafter, said valve being opened by the pressure of the hydraulic fluid to allow connate fluid to flow through passageways 81 down through test tube 83 and into a tail pipe 85 which forms a formation or test chamber for the reception of the test sample.

From the above description it is apparent that when packer setting valve 51 is opened, well fluid pressure will be effective to indirectly cause expansion of packers 65 and 75, to set the packers in the well bore, and also to indirectly cause opening of the test valve, in a manner to be described hereinafter, to allow formation fluid to flow down into the tail pipe 85 for entrapment of a sample.

Each of packers 65 and 75 is of similar construction and therefore the details of only one packer will be described. As best shown in Fig. 3, each packer comprises a hollow elongated resilient body 91 tightly fitting at its ends on its mandrel and being restrained against end bulging by a plurality of fabric and rubber dome-shaped heads 93 fitted onto the mandrel of the particular packer in question and serving to retain the packers against undue longitudinal expansion. The dome-shaped heads are adapted to be expanded axially into engagement with the walls of a well bore and against frusto-conical surfaces 95 formed on the packer heads, said surfaces serving to support the dome-shaped head after a predetermined amount of distortion thereof. Within each packer is an annular core 97 fitting onto the associated mandrel and being interiorly fluted to permit fluid passage between the mandrel and core to the opposite ends of the core, and around the ends to expand the packer. The packers during their expansion move away from their respective cores. Each packer is thick at its medial portion and thin at its ends so that the ends first expand and force heads 93 into engagement with the walls of the well bore.

The low pressure and the high pressure pistons 47 and 54 have a central air chamber 98 formed therein adapted to communicate through air ducts 98a with an annular air chamber 99 provided between the exterior of high pressure piston 54 and the interior of low pressure cylinder 49. There is a plug 100 closing the upper end of air chamber 98. When low pressure piston 47 is forced downwardly, part of the air within the annular chamber 99 is forced through ducts 98a into air chamber 98 so that the air resistance to movement of piston 47 is reduced to an unobjectionable value.

Packer setting valve 51 as previously mentioned forms a part of a compound valve member 53, the other valve of said compound valve member to be described hereinafter. At present, it suffices to say that the compound valve member is in a form of a rod having the lower end provided with a bore adapted to communicate with passages 43 by ports 101. Compound valve member 53 is connected to a connector rod 103 which slidably extends through a lock mechanism 105 to be presently described and into the lower end of a piston rod 107. Piston rod 107 is connected to a piston 109, the latter fitting within a piston housing 111. Piston 109 is adapted to be driven downwardly, thereby moving packer setting valve 51 to a position where the ports 101 thereof register with the passages 43, by means of the detonation cartridges 113

carried by a cartridge carrier 115 mounted in the upper end of piston housing 111. For causing detonation of the cartridges 113, there is provided a clock and battery arrangement 117 wired to the cartridges by leads 119. The clock mechanism is such that a predetermined time after the tool has been lowered into the well, the clock mechanism will close a switch supplying current from the battery to cartridges 113 to cause a detonation thereof, to drive piston 109 downwardly and, therefore, drive packer setting valve 51 downwardly.

The clock and battery mechanism 117 and therefore compound valve 53 is spring urged upwardly by an expansion spring 121. There is a releasing mandrel 123 extending from the upper end of the clock and battery mechanism 117 and through stem 27 and sub 22. Sub 22 contains a pair of spring pressed detents 125 adapted to snap into a groove 127 formed in releasing mandrel 123 to lock the mandrel to sub 22. Groove 127 is disposed beneath the detents, as shown in Fig. 1a, when the tool is being run into the well. The function of this releasing mandrel will be explained hereinafter.

It is apparent from the above description that after cartridges 113 have been fired it is necessary to hold packer setting valve 51 in registry with passages 43 against the resistance of spring 121. To perform this function, lock mechanism 105 previously mentioned is provided. Lock mechanism 105 is best shown in Figs. 5 through 8 and is contained within a lock sub or housing 131, which is secured to the lower end of piston housing 111 and to the upper end of a vacant housing 133, which in turn is secured at its lower end to the upper end of valve sub 41. The lock mechanism as shown in the above Figures includes piston rod 107 and connector rod 103, said piston rod having a reduced lower end 135 slidably fitting within a bore provided in the upper end of connector rod 103, said reduced portion 135 having ball receiving sockets 137 formed therein. Sockets 137 are disposed as the parts are depicted in Fig. 5 in registry with a pair of ports 139 formed in the upper end of connector rod 103. Surrounding the upper end of connector rod 103 is a locked housing 141 having a pair of locking balls 143 received within guides 145 formed in the locked housing. Locking balls 143 are urged inwardly by a circular coil tension spring 147.

It is apparent from the above construction that when the piston rod 107 is driven downwardly by the detonation of cartridges 113, ports 139 and sockets 137 are brought into registry with balls 143, said balls snapping into the ports and sockets to positively lock the connector rod against upward movement, and, therefore, locking packer setting valve 51 in a position with its ports 101 in lateral registry with well fluid inlet passages 43. Further operation of the locking mechanism will be explained hereinafter. For the present it is sufficient to say that locking balls 143 only releasably hold piston rod 107 against upward movement, and that said rod can be pulled upwardly, to the position shown in Fig. 8, to cam the locking balls 143 outwardly to release the connector rod for upward movement under the influence of a force 60 to be described, said rod serving to further outwardly cam the locking balls.

A summary of the operations up to this point shows that after the tool has been run into the well, the clock mechanism, which has been set at the surface, will close a switch at a predetermined time after the tool has been lowered into the well to supply electric current to cartridges 113, to cause detonation thereof to drive piston 109 downwardly and move packer setting valve 51 to open position. Well fluid under pressure will flow into the tool and be effective against low pressure piston 47 to force high pressure piston 51 downwardly, the latter-named piston forcing hydraulic fluid 57 through tubular mandrels 63 and 71 from whence the fluid can flow out through ports 67 and 77 and cause expansion of packers

65 and 75. The locking mechanism 105 will be effective to lock valve 51 in its open position.

Setting of the packers in the well will relieve the weight of the tool from spring 25, said spring being effective, upon a slight slackening of line 17 to force sleeve 23 and therefore sub 22 downwardly to allow detents 125 to snap into groove 127 of releasing mandrel 123 (see Fig. 2a). Detents 125 are not inserted into place until the rest of the tool is suspended from wire line 17 to compress spring 25 and bring the detent passages above groove 127 in releasing mandrel 123. Then, the detents are inserted into sub 22.

The construction of central packer head 69 and the construction and operation of the test valve, previously mentioned, will now be explained. As previously indicated, central packer head 69 and the lower end of mandrel 63 are so formed that hydraulic fluid can flow from tubular mandrel 63 into tubular mandrel 71. As best shown in Figs. 3 and 4, the lower end of upper tubular mandrel 63 is solid and formed with passages 151 communicating with a passage 153 formed in a nipple 155, the latter being secured to the lower end of tubular mandrel 63. Nipple 155 rests on a nut 157 threaded into the upper end of a plug 159 which is disposed within a central bore provided in central packer head 69. Fluid flowing through passage 153 flows into passages 161 formed in nut 157, plug 159 and central packer head 69, the lower end of passages 161 communicating with the interior of lower mandrel 71.

Test tube 83 previously mentioned fits within the lower end of plug 159 as shown in Fig. 4, said plug being centrally bored to receive a test valve 163 slidably fitting therewithin. Valve 163 is provided with suitable O rings for sealing engagement with plug 159. Test valve 163 is spring urged upwardly by an expansion spring 165 and is provided with a central bore terminating in lateral ports 167 which are adapted to be brought into registry with a cavity 168 formed in plug 159, said cavity communicating with previously mentioned formation test ports 81 (compare Figs. 1c, 3 and 4). When ports 167 are disposed within cavity 168, formation or test fluid can flow in through passages 81, through ports 167, down through test tube 83 and into tail pipe 85 where the sample is collected.

Limiting upward movement of test valve 163 is a nipple 171 threaded into plug 159, said nipple having a bleed passageway or orifice 173 extending therethrough for applying hydraulic fluid to the top of test valve 163. A resilient sleeve 175 covers lateral ports 177 provided in nipple 171. Orifice 173 is of such size that the hydraulic fluid can only bleed slowly therethrough so that packers 65 and 75 are fully expanded by the time that sufficient fluid has bled through nipple 171 to cause test valve 163 to move into a position where the ports thereof are disposed within cavity 168. Therefore, the packers are set before test fluid is allowed to pass down through test tube 83.

It is very desirous and in some operations necessary that the weight of drilling mud or well fluid not be imposed on the upper packer 65 and, therefore, an equalizing passageway is provided in the tool so as to by-pass the packers and allow the well fluid below and above the well packers to equalize pressure during a test operation. Referring to Figs. 1c and 3, upper top packer head 61 has lateral passages 181 formed therein in communication with the upper end of an upper equalizing tube 182, which is disposed within upper tubular mandrel 63 and has its lower end sealingly held within the lower solid end of said mandrel. Also formed within lower solid end of mandrel 63 are equalizing passages 185 communicating with passages 186 formed in central packer head 69, passages 186, as best shown in Fig. 4, communicating with the interior of a lower equalizing tube 189, which is fixed at its upper end to plug 159 and at its lower

end sealingly engages the interior of a reduced bore 191 formed in the lower end of tubular mandrel 71. In communication with equalizing tube 189 are lateral equalizing passages 193 formed in bottom packer head 73. It is apparent from the above passageway construction that well fluid pressure can be equalized above and below packers 65 and 75 at all times during testing operation thereby not imposing the weight of the drilling mud on the upper packer. The equalizing passages also insure that the mud pressure below the packer will be maintained even though some mud is lost during a testing operation.

Reference is now made to several later steps in the operation of the tool. After sufficient time has elapsed to ensure the entrapment of an adequate sample, it is desired to remove the wire line tester from the well. To accomplish this, an upper pull on wire line 17 is effected to compress spring 25 and raise or lift releasing mandrel 123 (which is not locked to sub 22) upwardly to cam locking ball 143 out of sockets 137 and raise stem 135 from the position shown in Fig. 6 to the position shown in Fig. 8. The well fluid pressure constantly urges rod 103 upwardly so that it follows the upward movement of stem 135, and further cams balls 143 outwardly to the positions shown in Fig. 8.

Compound valve 53 is carried upwardly by the upward movement of rod 103 to register lower ports 200 of a release valve 201 with passages 203 formed in valve sub 41, passages 203 communicating with the upper end of low pressure piston 47. Release valve 201 forms the second valve of compound valve member 53, valve 201 being formed by the provision of a bore 204 in the upper end of valve member 53, lateral ports 200 being adapted to communicate the bore with passages 203 when the compound valve member 53 is raised from the position shown in Fig. 2b to the position shown in Fig. 1b. There are upper lateral ports 207 communicating the interior of the bore 204 with the interior of vacant housing 133.

It is apparent from the above described parts that upon an upward pull on wire line 17, valve 51 is released from its locked position and under the influence of the well pressure moves upwardly to its closed position to align the ports 200 of release valve 201 with passageways 203 to allow the trapped well fluid under pressure in low pressure cylinder 49 to pass upwardly into the vacant housing 133. Low and high pressure pistons 47 and 53 are then free to move upwardly, under the influence of the pressure of the hydraulic fluid, to their initial positions, thereby allowing collapse of packers 65 and 75. When the pressure of the hydraulic fluid is reduced by the above operation, spring 165 of test valve 163 causes the valve to move upwardly from the position shown in Fig. 9 to the position shown in Fig. 4 to close the test valve and thereby entrap the test sample within tail pipe 85.

When going into the well, the high pressure in the space above and on the outside of sleeve 175 causes ports 177 to be closed, and therefore hydraulic fluid must pass only through orifice 173. When the packers are released, the low pressure on the outside of sleeve 175 permits fluid to escape through ports 177, thereby allowing valve 163 to close quickly under influence of spring 165.

Tail pipe 85 may contain a recorder if desired to show the shut-in pressure when the tail pipe is completely filled.

By the present invention an oil well formation fluid testing tool has been provided which can be suspended in a well by a wire line and operated to successfully set a pair of packers and then take a sample, and thereafter the packers can be collapsed and the sample entrapped. It will be appreciated that by providing a low pressure piston and a high pressure piston, the hydraulic fluid acted on by the high pressure piston will be under a pressure sufficiently higher than that of the well fluid to hold the packers against the well bore to create an effective seal. After the tool is brought to the surface the test

fluid can be drained from the tail pipe and the pressure recorder, if one is provided, and its chart removed.

While I have shown the preferred form of my invention, it is to be understood that various changes can be made in its construction by those skilled in the art without departing from the spirit of the invention as defined in the appended claims.

Having thus described my invention, what I claim and desire to secure by Letters Patent is:

1. An oil well formation fluid tester comprising a tool body having spaced expandable packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well bore to expand said packers and subsequently open said first valve, a second passage connecting said hydraulic means and the exterior of said tool body above said packers, a second valve for controlling the flow of well fluid through said second passage, means for opening said second valve to permit the hydrostatic pressure of the fluid in the well bore to actuate said hydraulic means, a second sealed chamber in said tool body, a third passage connecting said second chamber with said hydraulic means, a third valve in said third passage, and means connected to said second and third valves for subsequently closing said second valve and then opening said third valve to permit the well fluid trapped in said hydraulic means by the closing of said second valve to enter said second chamber, thus permitting said first valve to close and subsequently said packers to collapse.

2. In combination, wire line, tool body connected to the lower end of the wire line and adapted to be lowered into a well by said line, said body having spaced expandable packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well bore to expand said packers and subsequently open said first valve, a second passage connecting said hydraulic means and the exterior of said tool body above said packers, a second valve for controlling the flow of well fluid through said second passage, and means for opening said second valve to permit the hydrostatic pressure of the fluid in the well bore to actuate said hydraulic means.

3. In combination, a wire line, a tool body connected to the lower end of the wire line and adapted to be lowered into a well by said line, said body having spaced expandable packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well bore to expand said packers and subsequently open said first valve, a second passage connecting said hydraulic means and the exterior of said tool body above said packers, a second valve for controlling the flow of well fluid through said second passage, means for opening said second valve to permit the hydrostatic pressure of the fluid in the well bore to actuate said hydraulic means, a second sealed chamber in said tool body, a third passage connecting said second chamber with said hydraulic means, a third valve in said third passage, and means connected to said second and third valves for subsequently closing said second valve and then opening said third valve to permit the well fluid trapped in said hydraulic means by the closing of said second valve to enter said second chamber, thus permitting said first valve to close and subsequently said packers to collapse.

in said hydraulic means by the closing of said second valve to enter said second chamber, thus permitting said first valve to close and subsequently said packers to collapse.

4. An oil well formation fluid tester comprising a tool body having spaced expandable packers thereon, a body of hydraulic fluid in said tool body, a conduit connecting said body of fluid with the interior of said packers, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well bore to expand said packers and subsequently open said first valve, said hydraulic means comprising a low pressure piston adapted to be actuated by well fluid pressure, a high pressure piston connected to said low pressure piston for actuation thereby, said high pressure piston being in communication with said body of hydraulic fluid whereby a higher pressure than existing in the well fluid is created to expand the packers against the walls of the well bore, a second passage in said tool body providing communication between said low pressure piston and the exterior of said tool body above said packers, a second valve for controlling the flow of well fluid through said second passage, and means for opening said second valve to permit the hydrostatic pressure of the fluid in the well bore to actuate said hydraulic means.

5. An oil well formation fluid tester comprising a tool body having spaced expandable packers thereon, a body of hydraulic fluid in said tool body, a conduit connecting said body of fluid with the interior of said packers, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well bore to expand said packers and subsequently open said first valve, said hydraulic means comprising a low pressure piston adapted to be actuated by well fluid pressure, a high pressure piston connected to said low pressure piston for actuation thereby, said high pressure piston being in communication with said body of hydraulic fluid whereby a higher pressure than existing in the well fluid is created to expand the packers against the walls of the well bore, a second passage in said tool body providing communication between said low pressure piston and the exterior of said tool body above said packers, a second valve for controlling the flow of well fluid through said second passage, means for opening said second valve to permit the hydrostatic pressure of the fluid in the well bore to actuate said hydraulic means, a second sealed chamber in said tool body, a third passage in said tool body connecting said second chamber with said hydraulic means, a third valve in said third passage, and means connected to said second and third valves for subsequently closing said second valve and then opening said third valve to permit the well fluid trapped in said hydraulic means by the closing of said second valve to enter said second chamber, thus permitting said first valve to close and subsequently said packers to collapse.

6. In combination, a wire line, a tool body connected to the lower end of the wire line and adapted to be lowered into a well by said line, said body having spaced expandable packers thereon, a body of hydraulic fluid in said tool body, a conduit connecting said body of fluid with the interior of said packers, said tool body having a sample chamber formed therein, a first passage connecting the chamber with the exterior of the tool body at a point between the packers, a first valve in said first passage for controlling the flow of formation fluid therethrough, hydraulic means operatively connected to said packers

and said first valve and adapted to be actuated by the hydrostatic pressure of the fluid in the well to expand said packers and subsequently open said first valve, said hydraulic means comprising a low pressure piston adapted to be actuated by well fluid pressure, a high pressure piston connected to said low pressure piston for actuation thereby, said high pressure piston being in communication with said body of hydraulic fluid whereby a higher pressure than existing in the well fluid is created to expand the packers against the walls of the well bore, a second passage in said tool body providing communication between said low pressure piston and the exterior of said tool body above said packers, a second valve for controlling the flow of well fluid through said second passage, and means for opening said second valve to permit the hydrostatic pressure of the well bore to actuate said hydraulic means.

7. An oil well formation fluid tester comprising a tool body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, said means for opening said second valve including a detonatable charge in the tool body operable when detonated to open said second valve.

8. In combination, a wire line, a tool body connected to the lower end of the wire line and adapted to be lowered into a well by said line, said body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, said means for opening said second valve including a detonatable charge in the tool body operable when detonated to open said second valve.

9. An oil well formation fluid tester comprising a tool body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, a second sealed chamber in said tool body, said means for opening said second valve

including a detonatable charge in the tool body operable when detonated to open said second valve, a third passage in said tool body connecting said second chamber with said hydraulic means, a third valve in said third passage, and means connected to said second and third valves for subsequently closing said second valve and then opening said third valve to permit the well fluid trapped in said hydraulic means by closing of said second valve to enter said chamber, thus permitting said first valve to close and subsequently said packers to collapse.

10. An oil well formation fluid tester comprising a tool body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, said means for opening said second valve including a detonatable charge in the tool body operable when detonated to open said second valve, and a clock mechanism in said tool body operable to detonate said charge after a predetermined interval of time.

11. In combination, a wire line, a tool body connected to the lower end of the wire line and adapted to be lowered into a well by said line, said body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, said means for opening said second valve including a detonatable charge in the tool body operable when detonated to open said second valve, and a clock mechanism in said tool body operable to detonate said charge after a predetermined interval of time.

12. In combination, a wire line, a tool body connected to the lower end of the wire line and adapted to be lowered into a well by said line, said body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, said means for opening said second valve including a detonatable charge in the

tool body operable when detonated to open said second valve, a clock mechanism in said tool body operable to detonate said charge after a predetermined interval of time, a second sealed chamber in said tool body, a third passage in said tool body connecting said second chamber with said hydraulic means, a third valve in said third passage, and means connected to said second and third valves for subsequently closing said second valve and then opening said third valve to permit the well fluid trapped in said hydraulic means by closing of said second valve to enter said chamber, thus permitting said first valve to close and subsequently said packers to collapse.

13. An oil well formation fluid tester comprising a tool body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, and a fluid by-pass passage in said body communicating with the exterior of the tool body at points above and below the upper and lower packers, respectively, whereby the weight of the column of well fluid in the well is not imposed on the packers when set.

14. In combination, a wire line, a tool body connected to the lower end of the wire line and adapted to be lowered into the well by said line, said body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said body above said packers, a second valve for controlling the flow of well fluid through said second passage, means for opening said second valve to permit the hydrostatic pressure of the fluid in the well bore to actuate said hydraulic means, and a fluid by-pass passage in said body communicating with the exterior of the tool body at points above and below the upper and lower packers, respectively, whereby the weight of the column of well fluid in the well is not imposed on the packers when set.

15. An oil well formation fluid tester comprising a tool body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the

fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, a fluid by-pass passage in said body communicating with the exterior of the tool body at points above and below the upper and lower packers, respectively, whereby the weight of the column of well fluid in the well is not imposed on the packers when set, a second sealed chamber in said tool body, a third passage in said tool body connecting said second chamber with said hydraulic means, a third valve in said third passage, and means connected to said second and third valves for subsequently closing said second valve and then opening said third valve to permit the well fluid trapped in said hydraulic means by closing of said second valve to enter said chamber, thus permitting said first valve to close and subsequently said packers to collapse.

16. An oil well formation fluid tester comprising a tool body having spaced expandible packers thereon, said tool body having a sample chamber formed therein, a first passage connecting the chamber with the exterior of the tool body at a point between the packers, a first valve in said first passage for controlling the flow of formation fluid therethrough, hydraulic means operatively connected to said packers and said first valve and adapted to be actuated by the hydrostatic pressure of the fluid in the well to expand said packers and subsequently open said first valve, a second passage in said tool body providing communication between said hydraulic means and the exterior of said tool body above said packers, a second valve for controlling the flow of well fluid through said second passage, means for opening said second valve to permit the hydrostatic pressure of the fluid in the well bore to actuate said hydraulic means, said means for opening said second valve including a detonatable charge in the tool body operable when detonated to open said second valve, a clock mechanism in said tool body operable to detonate said charge after a predetermined interval of time, a fluid by-pass passage in said body communicating with the exterior of the tool body at points above and below the upper and lower packers, respectively, whereby the weight of the column of well fluid in the well is not imposed on the packers when set, a second sealed chamber in said tool body, a third passage in said tool body connecting said second chamber with said hydraulic means, a third valve in said third passage, and means connected to said second and third valves for subsequently closing said second valve and then opening said third valve to permit the well fluid trapped in said hydraulic means by closing of said second valve to enter said chamber, thus permitting said first valve to close and subsequently said packers to collapse.
